UNITED STATES PATENT OFFICE.

SAMUEL PUTRA, OF LANSFORD, PENNSYLVANIA.

MEASURING INSTRUMENT.

Application filed October 28, 1926. Serial No. 144,887.

This invention relates to new and useful improvements in carpenters' tools, and particularly to squares for marking rafter cuts.

The principal object of the invention is to provide a device of this character which can be easily and quickly set to the pitch of the roof to be built, and from such setting the carpenter may mark the top of a rafter for the plumb cut, the bottom of the rafter for the foot cut, and the step cut, adjacent the foot cut, which receives the wall plate, without a resetting of the parts of the tool.

Another object is to provide a tool of this character by means of which any unknown element of measurement, of the roof of a house may be quickly obtained upon knowledge of any one or more of the measurements thereof.

Another object is to provide a tool of this character by means of which the end cuts of the various rafters used in roofs may be easily and quickly obtained, as well as to ascertain the lengths of the various rafters.

Other objects and advantages will be apparent from the following description when taken in connection with the accompanying drawings.

In the drawings:

Figure 1 is a top plan view of the tool.

Figure 2 is a bottom plan view of the same.

Figure 3 is an enlarged transverse sectional view, on the line 3-3 of Figure 1, passing through the clamping bolt of the arms of the tool.

Figure 4 shows how the tool is used for marking the different cuts of a common rafter.

Figure 5 is a longitudinal sectional view on the line 5-5 of Figure 1.

Figure 6 is a plan view of a stairway stringer showing the marks for the riser and tread cuts.

Referring particularly to the accompanying drawings, 10 represents an elongated channel member, forming the main or body portion of the tool, said member having the offset extensions 11 and 12, at the opposite ends thereof. Formed longitudinally and centrally in the bottom wall of the member 10 is a slot 13. Pivotedly connected to the offset end 11 are the arms 14 and 15, the former of which is formed with a longitudinal central slot 16 in which the angular portion 17, of the shank of the pivot bolt 18 is disposed. The lower face of the arm 15 has

the shoulder 15', formed on its pivoted end, which extends transversely thereof, and is engaged by the adjacent edge of the arm 14 to maintain the latter in a position at right angles to the former. One longer wall of the slot 16 is beveled, and one side of the said angular portion of the bolt shank is correspondingly beveled for engagement with the said slot wall. A winged nut 19 is engaged on the bolt 18 for clamping the arms in different adjusted positions. Pivotedly connected to the arm 15, adjacent the inner end thereof, is a link 20, the other end of the link being offset, as shown at 21, and provided with a threaded opening in which is disposed a screw 22, said screw being also engaged through the plates 23, arranged on opposite faces of the member 10, and the slot of said member. Each of the plates is provided with the tongues 24 which engage in the slot to properly guide the plates longitudinally of the slot. One side of each of the plates 23 is curved, while the other one is straight, the straight side, as shown at 25, being arranged to register with the graduation marks on the member 10. The marks on the top face of the member indicate, at 24, degrees from 0 to 180; at 25, pitch per foot run, from one-quarter to eighteen inches, which gives top and bottom cuts for common rafters; at 26, cuts for sheathing of hip or valley and shingles; at 27, side cuts of jack rafters; at 28, side cuts of hip and valley rafters; and at 29, top and bottom cuts of hip and valley rafters. Carried by one side of the member 10, and visible through a slot 26 in said side, is a spirit level 27. The plate 28, and the top plate of the member 10 are secured by means of bolts 29, and may be readily removed, so that another plate, having different markings, may be substituted. The arm 14 is approximately ten inches in length, and has its faces marked with various subdivisions of the inches. The arm 12 may be longer or shorter.

Attention is called to Figure 4, wherein the use of the tool, for marking the different cuts of a rafter, is shown. The arms 14 and 15 are set to extend at right angles to each other. The operator then moves the member 10 until the plates 23 register with the marks indicating the pitch of the roof to be built. The member is then placed against the edge of the rafter and a line drawn across one

end, as shown at *a*, which represents the vertical line coincident with the outer face of the wall of the building, said line being made against the edge of the arm 15. A line *b*, is made on the rafter, intersecting the line *a*, the marking tool being drawn along the edge of the arm 14. This line *b*, represents the level of the building, that is horizontal to the ground line. In the edge of the rafter there are made the intersecting marks *c* and *d*, along which the carpenter saws to remove the triangular block *e*, leaving a correspondingly shaped notch in which is received the top plate of the wall of the building, whereby the lower end of the rafter is properly supported. The tool is then slipped to the other end of the rafter, and a mark *f* made thereacross, for the plumb cut, said mark being parallel with the mark *a*, and representing the inclined face which will rest against the ridge pole of the roof.

To mark off a string for a staircase, the tool is used in the manner just described with respect to the marks *c* and *d*, and marks *g* and *h* made on the side face of the string, representing the risers and treads of the steps.

In the extension 12 there is formed a small opening 30, and in the outer end of the arm 14 there is formed a similar opening 31. In the opposite end walls of the channel member 10 there are formed the

alinine openings 32 and 33, through which a person may sight, as when using the tool as a level or transit.

35

While I have described the device as particularly adapted for marking the angle cuts of rafters, I wish it understood that the device may be used for marking shingle cuts; as a drafting instrument, for various purposes; as a marking gage; for obtaining lengths of arcs of circles, and the chords, radiiuses and diameters thereof.

40

What is claimed is:

A carpenter's square comprising a body member having a longitudinal central slot and a reduced end forming a transverse shoulder, said reduced end being provided with an opening, an arm pivotally mounted on the reduced end of the body member and having a shoulder adjacent its pivoted end, a second arm having a longitudinal central slot slidable on the pivot of the first arm and arranged to engage with the shoulder of the first arm to form therewith a right angle, an arm pivoted to the first arm and having its other end slidably engaged in the slot of the body member and provided with an indicator, and means for clamping the first and second arms in right angular relation and being adapted to be moved on said pivot in such relation.
